(57) **CLAIM**

The ornamental design for animatronic character as shown and described.

DESCRIPTION

FIG. 1 is a front perspective view of an animatronic character according to a first embodiment position;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top view thereof;

FIG. 7 is a bottom view thereof;

FIG. 8 is a perspective view illustrating an animatronic character according to a second embodiment position;

FIG. 9 is a front elevational view thereof;

FIG. 10 is a rear elevational view thereof;

FIG. 11 is a left side elevational view thereof;

FIG. 12 is a right side elevational view thereof;

FIG. 13 is a top view thereof; and,

FIG. 14 is a bottom view thereof.

The broken lines shown are included for the purpose of illustrating the unclaimed portions of the article and form no part of the claimed design.
